UNITED STATES PATENT OFFICE.

CHARLES C. McINTOSH, DECEASED, LATE OF PORTLAND, OREGON, BY MARGARET McINTOSH, ADMINISTRATRIX, OF PORTLAND, OREGON.

CONVEYER MEANS FOR EXHAUST OR COOK BOXES.

1,176,228.

Specification of Letters Patent. Patented Mar. 21, 1916.

Application filed March 24, 1914. Serial No. 827,005.

To all whom it may concern:

Be it known that CHARLES C. McINTOSH, deceased, late a citizen of the United States, and resident of the city of Portland, Multnomah county, State of Oregon, did invent a certain new and useful Improvement in Conveyer Means for Exhaust or Cook Boxes, of which the following is a specification.

This invention relates in a general way to 10 the so-called exhaust box or cooker used in canneries, through which the cans are run for a definite period, and has particularly to do with the means for conveying the cans through the exhaust box.

15 One of the objects of this invention is to provide simple and positive can-conveying means operating in a horizontal plane.

To this end the improvement comprises a plurality of trackways arranged side by 20 side, cooperative advancing means for each trackway, and other advancing means connecting the ends of the adjacent trackways for carrying the can from one trackway to the other, and thus through the exhaust box.

25 A short-cut conveying means is provided whereby the time required for carrying the cans through the box is shortened without being required to change the speed of the operating device.

30 This invention also includes specific improvements in the advancing means of the trackway for rendering the same adjustable to cans of different sizes, and other features hereinafter fully set forth.

35 In the accompanying drawings: Figure 1 is a plan view of an exhaust box with the sides and steam plants, and embodying said improvements; Fig. 1^a is a fragmental side elevation showing a detail of construction

40 explained in the body of the specification; Fig. 1^b is another fragmental view showing a detail of construction concerning a removable rail located at the inlet end of the exhaust box, this rail being shown in broken

45 lines of Fig. 1; Fig. 2 is a vertical section taken on the line 2—2 of Fig. 1; Fig. 3 is a larger sized detail of a preferred type of an endless screw used as the conveyer, and illustrates the mode in which the cans are

50 advanced along a trackway; Fig. 4 is a sectional end elevation of the parts shown in Fig. 3, showing in addition the rails of the trackway over which the cans are moved by the conveyer means; Fig. 5 is a fragmental 55 front elevation of the machine, showing the

indicator element and the handle of the means provided for moving the rails of the trackways closer together and farther apart so as to receive cans of different sizes; Fig. 6 is a diagrammatic view showing the means 60 employed by me for so supporting the rails of the trackways as to render them laterally movable; and Fig. 7 is a larger-sized sectional view showing a portion of the screw conveyer running lengthwise of the track- 65 way, one of the transverse screw conveyers connecting the ends of adjacent trackways, and the adjustable guide coöperating with said transverse screw conveyer.

The device comprises a box or housing, *a*, 70 mounted on the supporting base legs *b*. A number of transverse frame members, *d*, having legs *d'* and cross beams *d''*, are mounted on the floor, *c*, of the box. The cross beams *d''* support the can conveyer 75 mechanism, while underneath and on the sides are the steam pipes *e*.

The can-conveying means consist of a plurality of trackways, *f*, arranged side by side, each having two rails *f'*, *f''*. The can is advanced along the trackway by a screw conveyer *g*, the thread *g'* of which is preferably made square-face so as to be adapted for engaging the crimped edge at the bottom of the cans *h*, as illustrated in Figs. 3 and 4. 80 The screw conveyers are driven through a motion-transmitting element *i*, and the connecting pinion elements *j*, *k*.

In order to adapt the trackways *f* to receive cans of different sizes, the rails of the 90 trackway are so arranged as to be laterally movable. For this purpose I prefer the arrangement more clearly illustrated in Figs. 1, 2 and 6. *l*, *m* are two transversely sliding bars supported in bearings *n* mounted 95 on the cross beams *d''*. Each sliding bar carries the chairs *l'*, *m'*, of one rail of the trackway. On the bottom of these chairs *l'*, *m'* are secured angle rails *f''*, and at the top of said chairs are fastened side rails *p'*. 100

Each slide bar is provided on its lower edge with a rack portion, as indicated at 12 and *m''* in Fig. 6. Supported on the lower side of the cross beams *d''* of the frame member *d* are bearings *d''* for the two parallel adjusting shafts *p*, *q*. Said shafts have pinned on them the pinions *p'*, *q'*, which mesh with said rack portions 12, *m''*. On the extreme end of the shafts *p*, *q* are the pinions *p''*, *q''* (see Figs. 1 and 5) which 110

mesh with each other. Fixed on the end of the shaft p , outside of the cook box, is an adjusting lever p^3 .

A circular scale with suitable graduations (shown in Fig. 5) guides the adjustment of the rails on the slide bars to any desired size of can. Journaled beneath and transverse to the trackways f are shafts r (see Figs. 1 and 7) and the transverse screw conveyers r' are pinned on these shafts. The transverse screw conveyers carry the can from one trackway to the other; openings being provided in the ends of the inner rails of adjacent trackways, as shown in Fig. 1. In order that the longitudinal conveyer (g) and the transverse conveyer (r') will lie in the same plane it is necessary to make the transverse screw conveyers of greater diameter. The transverse screw conveyers are constantly driven by the motion conveying element i by the gears r^2, r^3 . See Fig. 1. Bolted on the cross beams of the end frame members are the fixed Z-plates s . See detail Fig. 7. Parallel to the shafts r and on a shaft t^4 are journaled the arms t for adjusting the transverse guides. The latter carries a number of guide rails t^1, t^2, t^3 which are located in varying levels; and the surfaces of these guide rails are so inclined that by the rotation of the arm t about the shaft t^4 they may be arranged to lie in horizontal plane. The means for adjusting the arm t are shown in Fig. 1^a. An eccentric stop-lug u is rotatably mounted on a pin u' inside of the steam box, and the lever t^5 , fixed on the shaft t^4 , is supported in place by this stop. As the arm t has three positions, the stop lug u is made with three differently located flat faces, each arranged to so hold the lever arm t^5 as to bring either of the three surfaces t^2, t^3, t^1 of the guide rails into active position. These guide rails are provided only at that side of the screw conveyers r' toward which they turn, since the can would have a tendency to run off on such side only.

As designed, the time elapsing between the inlet and outlet of the cans from the box would be about five minutes; but there is also provided means by which this time may be cut down without making any change in the speed of the machine. Said means consist of a short cut, by which the travel of the can along two adjacent trackways is eliminated. For this purpose a removable rail section f^2 is provided in one rail f (see Figs. 1, 1^b.) This removable rail section has on its lower end an ear f^3 . A set screw f^4 , sliding on a bar f^5 , holds the removable rail section in place. When it is desired that the cans traverse all of the trackways, this removable rail section f^2 is placed in the position shown in Fig. 1^b, and shown in broken outline in Fig. 1; and when it is desired to eliminate the travel of the cans over the first two trackways, the rail section f^2 is

removed. In this way when the can has reached the first transverse screw conveyer indicated by A in Fig. 1, the can will be shunted directly over to the middle trackway, and then be carried up and down the 70 trackways.

What is claimed:

1. In a device of the character described, in combination with conveying means, a trackway comprising parallel slide-bars 75 movable transversely to the length of the trackway, chairs for one rail of the trackway carried by each slide bar, angle rails fastened on the bottom of the chairs and side rails fastened to the top of the chairs, 80 and means for moving the slide bars simultaneously in opposite directions.

2. In a device of the character described, in combination with conveying means, a trackway comprising parallel slide bars 85 movable transversely to the length of the trackway, chairs for one rail of the trackway carried by each slide bar, angle rails fastened on the bottom of the chairs and side rails fastened to the top of the chairs, 90 rack-portions at the bottom of each slide bar, pinions meshing with said rack portions, and means for simultaneously rotating the pinions.

3. In a device of the character described, 95 the combination of a plurality of parallel conveyers, guide rails at the sides of and separating such conveyers, the guide rail separating adjacent conveyers being made with a removable section located intermediate its ends, and an auxiliary transverse conveyer located at such removable section, whereby, when the latter is removed, the article carried between the guide rails of one conveyer is shunted to the adjacent conveyer.

4. In a device of the character described, the combination of a plurality of parallel screw conveyers, guide rails at the sides of and separating such conveyers, the guide rail separating adjacent conveyers being made with a removable section located intermediate its ends, and an auxiliary transverse conveyer screw located at such removable section, whereby, when the latter is removed, the article carried between the guide rails of one conveyer is shunted to the adjacent conveyer.

5. In a device of the character described, 120 the combination with can advancing means, of a supporting element coöperating with the advancing means and comprising a fulcrumed arm, a plurality of guide rails carried by the arm, such guide rails located in varying levels, and means for securing 125 said arm in place.

6. In a device of the character described, the combination with can advancing means, of a supporting element coöperating with the advancing means and comprising a ful- 130

crumpled arm, a plurality of guide rails carried by the arm, such guide rails located in varying levels, the guide rails of higher levels having their surfaces inclined so that when such surfaces are lowered by the rotation of said arm they will be placed in a horizontal plane, and means for securing said arm in place.

7. In a device of the character described, the combination with a screw conveyer, of a supporting element coöperating with the screw conveyer and comprising an arm ful-

crumpled on an axis parallel to that of the endless screw, a plurality of guide rails carried by the arm, such guide rails located 15 in varying levels, and means for securing said arm in place.
